UNITED STATES PATENT OFFICE.

FRED L. WILLIAMS, OF SAN FRANCISCO, CALIFORNIA.

FORCE-FEED LUBRICATING MECHANISM.

1,258,967.

Specification of Letters Patent. Patented Mar. 12, 1918.

Application filed June 10, 1916. Serial No. 102,884.

To all whom it may concern:

Be it known that I, FRED L. WILLIAMS, a citizen of the United States, residing at the city and county of San Francisco and State of California, have invented new and useful Improvements in Forced-Feed Lubricating Mechanism, of which the following is a specification.

This invention relates to a force feed lubricating mechanism.

An object of the invention is to provide means for lubricating the pistons, the piston pins and the crank pins in high compression, internal combustion engines, and particularly to provide a force feed mechanism which will deliver a lubricant under pressure between the surfaces to be lubricated at the time when they are subjected to the greatest pressure. Further objects will hereinafter appear.

The invention consists of the parts and the construction and combination of parts as hereinafter more fully described and claimed, having reference to the accompanying drawings, in which—

Fig. 1 is a side elevation of a gas engine, partly in section, showing the application of my invention.

Fig. 2 is a section on line 2—2 of Fig. 1.

Fig. 3 is a section, similar to Fig. 1, showing means for lubricating the crank and piston pins.

Fig. 4 is a plan section of the piston shown in Fig. 1, taken on a line above the lubricating mechanism mounted therein.

Fig. 5 is a side elevation of the connecting-rod shown in Fig. 3.

Fig. 6 is a detail view, partly in section, of the upper end of the connecting-rod shown in Fig. 1.

It has long been known that ordinary drop feed oiling is unsatisfactory for modern high speed machinery. The first improvement in the oiling of bearings was the ring oiler which permitted the use of the same oil over and over again in ample quantities, particularly when applied to stationary bearings.

With the introduction of high compression, internal combustion engines several lubricating difficulties were usually encountered especially the lubrication of the pistons, piston pins, connecting-rod bearings, etc. By oiling the piston to excess it was found that oil would sometimes pass the piston and enter the combustion chamber.

in this manner not only wasting oil but also permitting the formation of carbon which causes unnecessary wear and deterioration of the cylinder and piston. The crank and piston pins also had a tendency to overheat as the high pressure caused by explosion exerted caused a cracking of the oil film and consequently permitted overheating.

The main purpose of the present invention is to provide means for overcoming these difficulties by means of force feed lubrication, and particularly to provide a lubricating mechanism which will deliver a lubricant under pressure between the pins and the connecting-rod bearings at certain timed intervals during each cycle of revolution and which will also deliver oil under pressure between the pistons and cylinder walls at certain positions of the piston during each reciprocation.

This is accomplished as follows: Referring to the drawings in detail, and particularly Fig. 1, A indicates a gas engine cylinder; 2 the piston; 3 the piston pin; 4 the crank shaft; 5 the crank pin; and 6 the rod connecting the piston with the crank shaft. Suitably secured or formed integrally with the piston is a pair of cylinder members 7, and reciprocally mounted in each cylinder member is a piston 8 which is moved in one direction by means of a spring 9 and in the opposite direction by means of a cam member 10 formed at each end of the upper connecting rod bearing 11. The outer end of each piston member is provided with a head 12 to form a wearing surface between the cams 10 and the pistons 8. These cams are so shaped and positioned that the oscillating movement of the bearing 11, about the pin 3 during each reciprocation, will force the piston members 8 inwardly, while the springs 9 will force the pistons in an outward direction. The inner end of the cylinder barrel 7, shown on the left-hand side of Fig. 1, is connected through a pipe 13 with a shallow pocket 14 formed on one side of the piston. In a like manner a second pipe is shown which communicates with the inner end of said cylinder and a port 15 formed in the lower end of the piston at approximately right angles to the pocket 14.

A check valve 16 is interposed on each pipe and these check valves 16 serve the purpose of pump valves, or, in other words, permit circulation through the pump cylinder only in one direction. The pump cylin-

der shown on the right-hand side of Fig. 1, indicated at 7^a, is connected at its inner end through a pipe 17 with a port 18 formed near the upper end of the piston approximately opposite to the port 15; a second pipe 19, communicating with a pocket 20 formed in the exterior surface of the piston which is formed in alinement with, but above, the pocket 14. The pipe 19 is connected at the opposite end with the inner end of the cylinder 7^a, and check valves 21 are provided on each pipe to prevent circulation through the pump except in one direction. Also formed or secured on the upper end of 15 the connecting rod 6 is a pump cylinder 22. The lower end of this cylinder is connected through a pipe 23 with a port 24 formed in the lower side of the upper connecting rod bearing 11.

20 A second pipe 25, connected with the lower end of the cylinder, communicates with a strainer 26 and also with drain or return pockets formed in the lower side of the upper connecting rod bearing, said pockets 25 being similar to those shown at 27 in Fig. 6. A third pipe 28 connects with said drain pocket and secured on the lower end of said drain pipe is a drip cup 29 which is continuously supplied with oil from a wipe feed 30 formed on the end of a pipe 31 which is connected with a suitable source of supply. The cylinder 22 is also provided with a piston member similar to those previously described, said member being moved in one 35 direction by a spring, as shown, and in the opposite direction by a cam member 32 formed in the side of the piston wall.

The operation of the lubricating mechanism or the several force feed pumps here 40 shown will be as follows: Oil admitted between the cylinder and piston in the usual manner is gathered up by the upper and lower piston rings and by the pockets 14 and 20 formed in the exterior surface of 45 the piston. The pump 7 is actuated by the cooperating cam 10 during each downward stroke of the piston, and the inward movement of the piston 8 will cause sufficient pressure to operate the check valve 16 and 50 force the lubricant through the lower pipe which communicates with the port 15. A certain amount of oil is thus delivered under pressure between this side of the piston and the cylinder wall or between the contacting surfaces of the piston and cylinder 55 where the greatest pressure is exerted.

The opposite pump 7^a is similarly actuated by a cam member 10, but the actuated piston is permitted to move outwardly by 60 the spring action and to suck or fill the cylinder with oil taken from the pocket 20 through the pipe 19. The upward movement of the piston and the oscillating movement of the connecting rod will cause the 65 cam 10 to force the piston in and discharge

the contents of the cylinder through the pipe 17 and port 18 to a point between the upper end of the piston and the cylinder where the side thrust or pressure exerted upon the piston is greatest during the upward stroke. 70

It can thus be seen that a lubricant under pressure is delivered to each side of the piston at certain predetermined timed intervals during the reciprocal movement of the piston and at points between the contacting surfaces where the pressure happens to be greatest. The oil film thus injected or forced between the contacting surfaces not only reduces the frictional engagement of 80 the piston and cylinder but also reduces wear to a great extent. It, furthermore, permits a constant circulation of a given volume of oil over and over again, in this manner reducing the quantity required and 85 also preventing it from entering the firing end of the cylinder where it might carbonize and cause troubles as heretofore mentioned.

The action of the pump 22 and co-operating piston is similar to that described in connection with the cylinders 7 and 7^a. The oscillating movement of the rod causes the headed end of the piston to engage the cam 32, thereby transmitting a reciprocating 95 movement during each revolution which permits the piston to take in and discharge a given volume of oil during each reciprocation. This oil is taken from the end drain pockets of the bearing 11 through the pipe 100 23 and is discharged through the pipe 25 and the strainer 26 before it is finally injected between the bearing and the piston pin 3. The position of the cam 32 is such that the compression of the oiling piston 105 in the cylinder 22, which causes an injection of oil between the bearing and pin 3, takes place during the downward stroke of the piston or at the timed period when the pin and bearing are subjected to the greatest 110 pressure. The provision of the wipe feed 30 and the oil cock 29 permits a sufficient amount of oil to be constantly admitted so as to make up for any losses due to the consumption or leakage of oil at different 115 points.

By referring to Figs. 3, 5 and 6 it will be seen that a similar lubricating mechanism has been employed for the purpose of oiling the crank pins. The force feed cylinders 40 and 41 are in this instance carried by the connecting rod and the pistons mounted therein are engageable during each oscillating movement of the rod with lugs 42 formed on the interior of the piston. The 120 two cylinders employed are provided for lubricating the upper half of the connecting-rod crank pin bearings as it is well-known that the bearings are subjected to pressure both on the up and down stroke 125 130

of the piston. The pump shown on the left-hand side discharges during the up stroke of the piston through a pipe indicated at 43, while the cylinder 41 on the right-hand side discharges through a pipe 44 during the down stroke of the piston. The pipes 44 and 43 are connected at 45 with a pipe 46 which enters the upper half of the connecting rod crank pin bearings. Oil is in 10 this manner introduced under pressure between the crank pins and bearings both during the up and down stroke, and this oil, when escaping, is collected in a drain pocket 47 formed in the lower half of the bearing and is returned from this point through a suction pipe 48 which connects with the branch pipes 49 and 50, connected with the lower ends of the cylinders.

Strainers or filters, such as indicated at 20 51, of any suitable construction may be interposed on each pipe line to remove any solid particles which might be liberated through wear between the crank pins and bearings.

25 The force feed cylinders with the connected pipes and valves constructed and mounted, as here shown, may be sufficiently small to prevent interference with any of the moving parts of the remaining mechanism. It is, furthermore, possible to mount the cylinders either on the rod or on the pistons, as shown, the action being the same in either instance.

30 The materials and finish of the several parts of the mechanism are such as the experience and judgment of the manufacturer may dictate.

I wish it understood that various changes in the form, proportions and minor details 40 of construction may be resorted to within the scope of the appended claims and that I do not wish to limit myself to the specific design and construction here shown.

Having thus described my invention, what 45 I claim and desire to secure by Letters Patent is—

1. In a lubricating oil feed for reciprocating engines, a pair of pumps arranged within the piston on opposite sides of the 50 connecting rod, conduits leading to and from the pump, and oppositely projecting cam parts carried by the connecting rod for operating the pumps on swinging movement of the connecting rod.

55 2. In combination with a cylinder, a reciprocating piston therein, a connecting rod connected to the piston, and a crank pin connected to the rod, a lubricant collection pocket provided in one of the bearing surfaces of said parts, and a pump mechanism operable by and upon relative movement between the piston and rod for delivering the lubricant from the pocket to a bearing surface between said parts.

60 3. In a lubricating oil feed for recipro-

cating engines, a piston and its connecting rod, a pump cylinder extending inwardly from the piston toward the connecting rod, a plunger in the cylinder operable by the rod, an inlet conduit leading from the 70 periphery of the piston in one side of the pump cylinder, and an outlet leading from the opposite side of the pump cylinder to the periphery of the piston.

4. In a lubricating oil feed for reciprocating engines, a piston, a connecting rod, a pair of oil pumps arranged on opposite sides of one of the aforesaid elements, and a pair of cams carried by the other of said elements and engaging the pump plungers for operating the latter on sidewise movement of the connecting rod.

5. The combination with a cylinder and a piston reciprocally mounted therein, the piston pin, the crank pin, and the connecting 85 rod of an internal combustion engine, of a plurality of pumps intermittently actuated by the piston movement for delivering a lubricant under pressure between the pins and the connecting rod bearings and between 90 the pistons and cylinder walls.

6. The combination with a cylinder and a piston reciprocally mounted therein, the piston pin, the crank pin, and the connecting rod of an internal combustion engine, of a 95 plurality of pumps intermittently actuated by the piston movement for delivering a lubricant under pressure between the pins and the connecting rod bearings and between the pistons and cylinder walls, and means 100 for circulating said lubricant.

7. In a lubricating oil feed for reciprocating engines, a piston having a collection pocket in its periphery, an oil pump extending inwardly from the inner wall of the 105 piston, conduits leading from the pocket to the pump and from the latter to the exterior of the piston, and a cam provided on the connecting rod to partake of the sidewise movement thereof in operating the pump. 110

8. In a lubricating oil feed for reciprocating engines, a piston and its connecting rod, a cam carried by one of said elements, and a horizontally disposed oil pump carried by the other element with its plunger engaging 115 the cam.

9. In a lubricating oil feed for reciprocating engines, a piston and its connecting rod, a pair of oppositely extending cams on the rod adjacent its connection with the piston, 120 and a pair of inwardly extending oil pumps integrally formed on the interior of the cylinder and having spring pressed plungers engaging the cams.

10. In a lubricating oil feed for reciprocating engines, an oil pump operable through the relative movement of the piston and its connecting rod, and means for supplying oil to the pump including a fixed gravity feed and a drip cup connected with the oil pump 130

and positioned to wipe the underside of the gravity feed on operation of the piston.

11. In a lubricating oil feed for reciprocating engines, a piston, a connecting rod, an oil pump carried by the rod for force-feeding a lubricant to a bearing surface and including a spring retracted plunger, and a transversely extending cam projecting inwardly from the inner wall of the piston and alongside the rod to operate the pump plunger on sidewise movement of the connecting rod.

12. In a lubricating oil feed for reciprocating engines, a piston and its connecting rod, a pair of inwardly extending lugs on the inner wall of the piston, and a pair of longitudinally arranged oil pumps on the connecting rod having their plungers constantly and directly engaging the lugs for being operated thereby on sidewise movement of the rod.

13. In combination, a reciprocating piston, a connecting rod pivoted thereto, a cylinder for the piston, a crank shaft connected with the connecting rod, a force feed mechanism for lubricating a bearing surface between two of said elements, means for collecting the superfluous oil from the bearing surface and reapplying it to the same, a drip cup on the connecting rod, and a wipe feed ar-

ranged in the path of the cup for replenishing the supply of oil.

14. In combination, a cylinder, a reciprocating piston therein having a peripheral collection pocket, an oil feeding conduit leading from the pocket through the piston to the periphery of the latter, and mechanically operated means arranged within the piston for impelling the lubricant from the pocket through the conduit.

15. In a lubricating oil feed for reciprocating engines, a piston and its connecting rod, a pump cylinder extending inwardly from the piston toward the connecting rod, a plunger in the cylinder operable by the rod, an inlet conduit leading from the periphery of the piston to the pump cylinder, an outlet leading from the latter to the periphery of the piston, a cam opposing the cylinder and carried by the piston for operating the plunger, and spring means holding the plunger against the cam.

In testimony whereof I have hereunto set my hand in the presence of two subscribing witnesses.

FRED L. WILLIAMS.
